US00D853405S

(12) **United States Design Patent** (10) **Patent No.:** **US D853,405 S**
(45) **Date of Patent:** **** Jul. 9, 2019**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Yongman Park**, Yongin-si (KR); **Jooyoun Paek**, Seoul (KR); **Jakyung Lee**, Seoul (KR); **Heonoo Lee**, Seoul (KR)

(73) Assignee: **SAMSUNG ELECTRONICS CO., LTD.**, Suwon-si (KR)

(**) Term: **15 Years**

(21) Appl. No.: **29/561,996**

(22) Filed: **Apr. 21, 2016**

(30) **Foreign Application Priority Data**

Nov. 18, 2015 (KR) 30-2015-0058184

(51) LOC (11) Cl. **14-04**

(52) U.S. Cl.

USPC **D14/485**

(58) **Field of Classification Search**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design; and,

FIG. 3 is a front view of a third embodiment of a display screen or portion thereof with graphical user interface showing our new design.

The broken line showing of the display screen or portion thereof forms no part of the claimed design. The portions of the graphical user interface shown in broken line form no part of the claimed design.

1 Claim, 3 Drawing Sheets
